UNITED STATES PATENT OFFICE.

HERBERT BROOKS, OF YEOVIL, ENGLAND, ASSIGNOR TO PETTERS LIMITED, OF YEOVIL, ENGLAND.

MEANS FOR REVERSING INTERNAL-COMBUSTION ENGINES.

1,373,484.

Specification of Letters Patent.

Patented Apr. 5, 1921.

Application filed July 19, 1920. Serial No. 397,247.

To all whom it may concern:

Be it known that I, HERBERT BROOKS, resident of "Whitleigh," St. Michael's avenue, Yeovil, in the county of Somerset, England, 5 a subject of the King of Great Britain and Ireland, have invented certain new and useful Improved Means for Reversing Internal-Combustion Engines, of which the following is a specification.

10 This invention relates to internal combustion engines of the kind in which for effecting a reversal of rotation, a stroke of increased length is given to the fuel pump by the pump operating gear as used for 15 normal running, and has for its object to provide improved apparatus for reversing the direction of rotation.

In the apparatus for effecting the reversal of internal combustion engines heretofore 20 proposed the fuel pump is generally first put out of action in order to slow down the engine prior to reversing, whereupon an inertia governor causes the fuel pump to supply an abnormally large charge to the engine thus giving a premature impulse and 25 effecting the reversal.

In the improved apparatus according to my invention the fuel pump continues to be operated as in normal running but for slowing down the engine prior to reversal I provide means for rendering the stroke of the pump ineffective thus suppressing the injection of fuel into the combustion chamber until the necessary reduction in speed 30 has been made. For effecting the reversal I provide mechanism which is brought into operation by a suitable governing device adapted to render inoperative the aforesaid means and permit an increased effective 35 stroke being given to the fuel pump to effect the reversal of rotation.

Constructions embodying my invention are illustrated in the accompanying drawings, in which—

40 Figure 1 is a perspective view showing apparatus for suppressing the injection of fuel into the combustion chamber to cause the engine to slow down prior to reversal, also mechanism operated by an inertia governor which permits an increased effective 45 stroke being given to the fuel pump by which the reversal of direction of rotation is effected;

Fig. 1^a shows diagrammatically means

for adapting my invention for use in a two-cylinder engine in conjunction with the device specified in my British patent No. 121,511; Fig. 2 is a perspective view showing a device operated from a moving part of the engine for actuating the apparatus shown in Fig. 1; and Fig. 2^a is a perspective view, partly broken away, illustrating means for operating said device.

Referring to Figs. 1 and 2 of the drawings, a fuel pump 1 is shown provided with a spring pressed plunger 2 which is struck by the roller 3 carried on a pin 4 attached to a rocking lever or arm 5 which receives a rocking motion from the eccentric rod 6. The roller 3 is made with two diameters, 60 the small diameter for giving the normal stroke to the pump plunger and the large diameter for giving an increased stroke. Attached to the fuel pump suction valve chamber (not shown) is a fitting 7 in which 65 works a rod 8 so arranged that when raised by a lever 9 it lifts the suction valve off its seat. The lever 9 is pivoted on a bracket 10 and connected to the actuating device by 70 a rod 11.

The actuating device shown in Fig. 2 comprises a cam or the like 12 carried by a bracket 13 and rotated from a moving part of the engine, a forked lever 14 one end of which is pivoted on a swivel 15, and a trip lever 16 pivoted on one of the fork ends of the lever 14 and held against a stop 17 by the spring 18. Another trip lever and 75 spring (not shown) is fitted to the other fork end of the lever 14.

On the bracket 13 is pivoted a hand operating lever 19 to which is connected a rod 20 working in a hole drilled in the forked lever 14. On the rod 20 are mounted two springs 21 and 22, one end of each spring 80 being adapted to bear against the lever 14 and the other end of each spring being adapted to bear against the adjusting nuts 37 on the rod 20.

Fig. 2^a is shown means for rotating the 100 cam 12 comprising a pin 55 which is attached to the lower end of the eccentric rod 6, and thus has an approximately circular motion. A central slot 57 of sufficient length is provided in the cam wheel 12, in 105 which works a sliding block 56 mounted loosely on the pin 55, the sliding block conforming to the particular motion given by

the eccentric rod and thus transmitting a rotary motion to the said cam wheel. It will be understood that with the reversal of rotation of the engine, the direction of rotation of the cam 12 is also reversed. For example, if the rotation of the cam is as indicated by the arrows in Figs. 2 and 2^a, when the engine is running in the forward direction, the cam 12 will rotate in the direction opposite that indicated by the said arrow when the engine is running in the reverse direction. The cam 12 is provided with one or more depressions 120, the purpose of which is described hereinafter.

15 If it is not convenient to employ the form of drive described above, then the said cam may be driven by means of ordinary gear wheels.

Again referring to Fig. 1 the bracket 20 carries bearings 24 and 25 supporting a spindle 23 and when a reversal of the direction of rotation is required this spindle is forced forward by an inertia governor 26, which engages the spindle 23 only when the speed of the engine is sufficiently slow, but at higher speeds is given an upward movement to clear the spindle 23 by passing over the inclined plane 34, said upward movement being controlled by a spring 340. 25 Upon the bearing 24 a lever 27 is pivoted on a pin 28, one end of the lever 27 being adapted to make contact with the roller 3 and at the other end is mounted a roller 29 adapted to bear against a step or cam 30 on the spindle 23. Part of the spindle 23 where supported in the bearing 25 is turned smaller in diameter to take a spring 31. To the lever 9 is connected one end of a rod 32 the other end of which is adapted to bear 30 against the step 30; the lower end of a shouldered rod 33 is also connected to the lever 9.

In order to make it impossible for the governor to operate the spindle 23 when the reversing mechanism is out of use, as for instance when it is required to stop the engine, the top end of the rod 33 passes up through the inclined plane 34 and lifts the inertia governor 26 clear of the spindle 23, 45 being held in this position by the pressure of the spring 35 on the lever 9. The shoulder 36 is adapted to bear against the underside of the bracket 10 for the purpose of restricting the movement of the lever 9 and 50 rod 33.

In operation when it is desired to reverse the direction of rotation the above described apparatus works in the following manner:—

If the direction of rotation of the engine 60 is such as to rotate the cam 12 in the direction indicated by the arrow shown in Fig. 2 then in order to reverse the direction, the hand operating lever 19 is pushed forward, compressing the spring 21 thus exerting a 65 side pressure on the forked lever 14, and

forcing the trip lever 16 across the face of the cam 12, thus giving a downward motion to the lever 14, the one or more depressions 120 in the cam 12 making the action more positive. That is to say, the forked trip 70 lever 14 (Fig. 2) is pushed up against the cam 12 on one side or the other, according to the direction in which the engine is running at the time when reversal is to be effected and the friction between the periphery of the cam and the forked lever would normally carry the said lever downward without the depressions 120; but, by providing one or more of these depressions the action of the spring 21 (or spring 22) 80 forces the trip lever 16 into the said depression, which positively engages the edge of the trip lever 16 and thus positively moves the forked lever 14 downward. In fact, the depressions add a positive engagement 85 to a frictional engagement, thus making the movement more certain. This motion is transmitted to the lever 9 by the rod 11, giving a downward motion to the shouldered rod 33, and an upward motion at the 90 other end of the lever 9, thus raising the rod 32 and bringing it in contact with the step 30; at the same time the rod 8 is raised which lifts the fuel pump suction valve off its seat. This throws the fuel pump out of 95 action, the fuel being forced back into the suction pipe instead of through the delivery pipe to the combustion chamber. The engine slackens speed immediately and when the speed is reduced sufficiently to insure a 100 reversal the inertia governor 26 engages with the spindle 23 driving this forward. In its forward movement the roller 29 rides over the step 30 and gives a cross motion to the lever 27, whereby the roller 3 is moved 105 along the pin 4 bringing the large diameter of the roller into position for striking the pump plunger 2. At the same time the rod 32 is forced downward by the step 30 and allows the spring 35 to lower the rod 8, thus 110 returning the fuel pump suction valve to its seating and leaving the fuel pump in its working position.

The pressure of the step 30 which forces the rod 32 downward serves likewise to raise 115 the rod 11 on the other side of the lever 9, whereby the forked lever 14 is raised to its rest position. This action being positive overcomes the downward effect of the pressure of the cam 12 on the lever 16, the 120 springs 21 and 22 allowing the lever 16 to yield by moving out radially on the face of the cam. The fuel on entering the heated combustion chamber vaporizes and on mixing with the air compressed in the cylinder explodes before the piston reaches the top center and drives the piston in the reverse direction so that the engine rotates in the opposite direction. As the inertia governor moves backward, the spring 31 re- 125 130

turns the spindle 23 to its normal position and the roller 3 is returned by a spring to its position for normal running so that on the next compression stroke the small diameter 5 of the roller 3 strikes the fuel pump plunger 2 and gives the normal injection whereby the engine regains its speed in the reversed direction.

It will be understood that the reversal 10 results from the earlier explosion obtained by the increased charge of fuel, of which the increased portion is injected into the combustion chamber earlier than the normal injection.

15 When the engine commences to rotate in the opposite direction the cam 12 also runs in the opposite direction, and an upward motion is given to the trip lever 16 upon making contact with the one or more depressions 120 in the face of the cam, thus bringing the other end away from the stop pin 17. This action allows the spring 35 to keep the lever 14 in its rest position; the actuating device thus being put out of 20 action, normal injections are resumed, and the engine continues to run in the reversed direction. Immediately the hand lever is released the springs 21 and 22 return the forked lever 14 to its neutral position and 25 the trip lever 16 is brought back against the stop 17 by the spring 18.

If the engine is to be again reversed, the 30 lever 19 must be pulled backward to bring the actuating device into operation the other trip lever (not shown) is then brought into contact with the face of the cam 12 whereupon the reversal is again effected in the manner described above, but in the opposite direction.

40 The actuating device shown in Fig. 2 is arranged not only to be momentarily thrown out of action at the time of the increased stroke of the fuel pump but to become completely inoperative as soon as the direction of 45 rotation is reversed, whereby the normal injection is again resumed. If, however, reversal has not taken place the aforesaid actuating device by reason of the cam rotating in the same direction again comes into 50 operation as soon as the aforesaid positive action transmitted from the step 30 is released, causing the engine speed to be reduced again thus bringing into action the governing device and the process is repeated 55 any number of times until a reversal is effected.

The above described reversing arrangement is adapted for single cylinder engines, but the invention can also be adapted for 60 use on multi-cylinder engines using in conjunction therewith the device illustrated in Fig. 1^A as applied to a two cylinder engine.

Referring to Fig. 1^A, 38 is a body to which are connected the fuel delivery pipes 65 leading from the fuel pumps (not shown)

and pipes leading to the cylinders corresponding to the pumps. A valve 39 with a shoulder 40 is kept on its seat 41 by a spring 42 pressing on the inside of the collar 43. The valve can be forced 70 off its seat either by means of the lever 27, when brought into operation by the inertia governor, or by the hand lever 44, which is pivoted at 45 and may be kept open when desired by placing the 75 swivel catch piece 46 in position as shown in the drawing. The delivery pipe from the fuel pump which supplies the increased charge for reversal is connected to the body 80 38 at the threaded part 47, and the pipe leading to the cylinder corresponding to said pump is connected to the threaded part 48. The delivery pipe from the other fuel pump is connected to the threaded part 49 and the pipe leading to the cylinder, corresponding to said pump, is connected to the threaded part 50. With the valve 39 in its closed position, the fuel delivered by the first mentioned pump passes through the holes 51 and 52 and thence to the cylinder normally 90 supplied by said pump, and the fuel delivered by the second pump passes through the holes 53 and 54 and thence to the cylinder normally supplied by the said pump. With the valve pressed in slightly and the 95 catch piece 46 in position as shown, each pump delivers a charge to its corresponding cylinder at the normal timing and also a supplementary charge at an advanced timing to the cylinder not corresponding, the 100 timing of the advanced charge being controlled by the angular relation of the pump operating gear to a moving part of the engine as described in my aforesaid British Patent No. 121,511.

105 When the device is used in conjunction with the reversing mechanism, at the time the cross motion is given to the lever 27, one end of the lever moves the roller 3 to the right and the other end of the said lever moves to the left and presses in the valve 39 so that the valve stem totally covers the hole 52; then when the effective stroke is given to the pump which supplies the increased charge, the latter is wholly diverted 110 to the other cylinder, the fuel passing from the hole 51 through the hole 54 to the said cylinder. The valve 39 is returned to its seat by the spring 42, when the lever 27 returns to its rest position, thereby permitting 115 the pumps to supply their respective cylinders.

120 My invention can be carried into effect in various ways and by various constructions other than those illustrated and the said other constructions would be within the scope of my invention. It should therefore be understood that I in no way limit myself to the precise constructions illustrated as these are only given as examples.

What I claim and desire to secure by Letters Patent is:—

1. The method of reversing the direction of rotation of internal combustion engines of the kind in which liquid fuel is supplied to an engine cylinder by means of a fuel pump and plunger operated from the crank shaft of the engine, which consists in diverting the charge supplied by the fuel pump so as to prevent the charge from entering the combustion chamber of the cylinder in order to reduce the engine speed previous to reversal, then rendering inoperative the means employed for the said diversion of the fuel so as to permit the fuel to again enter the combustion chamber of the cylinder, and supplying an earlier and abnormally large injection into the cylinder to effect the reversal.
2. Apparatus for reversing the direction of rotation of internal combustion engines of the kind in which liquid fuel is supplied to an engine cylinder by means of a fuel pump operated from the crank shaft of the engine, comprising in combination with a liquid fuel supply pump and plunger, means for imparting a normal running stroke to the fuel pump plunger, means for diverting from the engine cylinder the charge supplied by the normal running stroke of the fuel pump plunger in order to reduce the engine speed previous to reversal, means actuated by the reduction of speed of the engine for rendering inoperative said fuel-diverting means, and means for imparting an earlier and longer stroke to the fuel pump plunger for effecting reversal.
3. Apparatus for reversing the direction of rotation of internal combustion engines of the kind in which liquid fuel is supplied to an engine cylinder by means of a fuel pump operated from the crank shaft of the engine, comprising in combination with a liquid fuel supply pump and plunger, a rocking lever for actuating the fuel pump, means for rocking the lever, a pin on the operating end of the lever, a stepped roller mounted on the pin for engaging the fuel pump plunger, the part of the roller having the smaller diameter for imparting the normal running stroke and the part of the roller having the larger diameter for imparting the reversing stroke to the fuel pump plunger, a spring tending to hold the roller in position to effect the normal running stroke of the fuel pump plunger, a lever adapted to engage the roller to move it against the action of the spring into position to effect the reversing stroke of the fuel pump plunger, an inertia device adapted to actuate said lever when the speed of the engine is sufficiently reduced, and means for diverting from the engine cylinder the charge supplied by the normal running

stroke of the fuel pump plunger in order to reduce the engine speed prior to reversal.

4. In apparatus for reversing the direction of rotation of internal combustion engines, the combination with a liquid fuel supply pump and pump plunger, of means for imparting a normal running stroke to the pump plunger, means for imparting a reversing stroke to the pump plunger, means for preventing the injection of the fuel supplied by the normal running stroke of the pump plunger into the engine cylinder in order to reduce the engine speed prior to reversal, means dependent on the consequent reduction of speed for operating a reversing stroke of the pump plunger and for rendering inoperative said injection preventing means, and means dependent upon the reversal being effected for again causing the normal running operation of the pump.

5. Apparatus for reversing the direction of rotation of multi-cylinder internal combustion engines, comprising the combination with a liquid fuel supply pump and pump plunger for each cylinder, of means for imparting a normal running stroke to each fuel pump plunger, means for imparting a reversing stroke to a pump plunger, a distributing valve casing for controlling the communication of the fuel pump with the respective engine cylinders, a connecting pipe from the delivery side of each pump to the said valve casing, a connection from the said casing to the combustion chamber of each cylinder, a valve in said casing normally opening the communication between each fuel pump and a plurality of cylinders, means for preventing the injection of the fuel supply by the normal running strokes of the pump plungers into the engine cylinders in order to reduce the engine speed prior to reversal, a device actuated by the reduction of speed for rendering inoperative said injection-preventing means and for operating a reversing stroke of the reversing pump plunger, a connection from said device to the said distributing valve to move the valve to close the communication between the reversing pump and the corresponding cylinder and to cause the whole of the reversing charge to be injected into another cylinder, and means dependent upon the reversal being effected for again causing the normal operation of all the fuel pumps.

6. Apparatus for reversing the direction of rotation of internal combustion engines comprising in combination a liquid fuel supply pump and pump plunger, means for imparting a normal running stroke to the pump plunger, means for imparting a reversing stroke to the pump plunger, a pivoted lever for lifting the suction valve of

the pump from its seat to prevent the injection of fuel supplied by the pump into the engine cylinder in order to reduce the engine speed prior to reversal, means for 5 operating said lever at will from a moving part of the engine when it is desired to effect the reversal. An inertia device acted upon by the pump-operating means, a connection from said lever to the inertia device 10 normally restraining the action of the latter, a member adapted to be actuated by the inertia device when the latter is released by the operation of the said lever for effecting reversal and when the speed of the en-

gine is sufficiently reduced, a connection 15 actuated by said member to operate a reversing stroke of the fuel pump plunger, another connection actuated by said member for returning said pivoted lever to its normal position to allow the suction valve 20 of the pump to return to its seat to resume normal running, and means for returning the operating parts to running position after reversal.

In testimony whereof I have signed my 25 name to this specification.

HERBERT BROOKS.
